UNITED STATES PATENT OFFICE.

WILLIAM DE BROCK, OF MILWAUKEE, WISCONSIN.

PNEUMATIC VALVE-OPERATING MECHANISM FOR HYDRAULIC ELEVATORS.

SPECIFICATION forming part of Letters Patent No. 367,794, dated August 9, 1887.

Application filed November 23, 1886. Serial No. 219,555. (No model.)

To all whom it may concern:

Be it known that I, WILLIAM DE BROCK, of Milwaukee, in the county of Milwaukee and State of Wisconsin, have invented new and useful Improvements in Pneumatic-Valve-Operating Mechanism for Hydraulic Elevators; and I do hereby declare the following to be a full, clear, and exact description of said invention, reference being had to the accompanying drawings, and to the letters or figures of reference marked thereon, which form a part of this specification.

Figure 1 represents an elevator in section, and a side view of the ordinary hydraulic mechanism for operating the same, provided with my pneumatic-valve-operating device. Fig. 2 represents a vertical section of the valve-cylinder and water-controlling valves shown in Fig. 1 in connection with the valve-operating device. Fig. 3 represents a vertical section, and Fig. 4 a side view, of an air-cock by which the course of the air is controlled between the air-reservoir and the valve-operating mechanism. Fig. 5 represents a side view of the air-pipes in connection with air-cocks located at the respective floors of the building.

Like parts are represented by the same reference-letters through the several views.

30 The elevator A, hydraulic engine or motor B, and the water-controlling mechanism, consisting of the valve-chamber C, with inlet-duct *a*, outlet-duct *b*, exhaust-duct *g*, and sliding valves or pistons *c*, *d*, and *e*, are all formed in the ordinary way, and form no part of my present invention.

40 Heretofore the water-controlling valves *c*, *d*, and *e* have been governed by moving a cable suspended through the elevator, such cable being drawn downward to start the elevator in one direction and upward to reverse the movement of the elevator. By my improvement such valve-controlling cable is dispensed with, and the said water-controlling valves are entirely controlled by compressed air. To the protruding ends of the valve-rod D are connected a piston-rod, D', and a piston, E, operating in an air-tight cylinder, F.

45 The piston E is forced downward by admitting compressed air above it through the air-duct G, whereby the water-controlling valves *c*, *d*, and *e* are also moved downward in the

cylinder C, thus opening communication from the inlet-pipe *a* through the cylinder C and thence through the duct *b*. The movement of the water-controlling valves is reversed by admitting the condensed air through the air-tube H, whereby the piston E with the connecting-rods and water-valves are thrown upward when the water escapes past the valve *c* through the pipes *b* and *g*. As the water is admitted upon one side of the piston through one of said air-pipes, the air upon the opposite side exhausts through the other air-pipe, and when desirous to stop the elevator the faucet 65 is so turned as to exhaust from each side of said piston E when said piston is thrown to the center of said cylinder F by the spiral springs *a'* *a'*, whereby water is both excluded from the motor B and prevented from escaping, thereby causing the motor and elevator to remain at rest.

70 The compressed air used for controlling the movement of the valves is confined in an air-reservoir, J, and it is controlled in its course 75 therefrom to and exhausted from the respective sides of said piston by the air-controlling cock K. The air is conducted from the air-reservoir J to said air-cock K through the air-tube L, and from thence to the respective sides 80 of the piston, as stated, through the air-pipes G and H.

When desirous to raise the elevator, the handle M of the air-cock is thrown toward the left, in the position shown by dotted lines at M', 85 Fig. 3, whereby communication is opened between the inlet air-pipe L and the outlet air-pipe G through the air-duct O, which duct is by such movement of the handle brought into the position indicated by dotted lines at O'. 90 The air thus admitted to the pipe G enters the cylinder F above the piston E, thus forcing said piston downward, as mentioned, whereby the water-controlling valves are opened and the elevator caused to ascend. By a reverse 95 movement of the handle M to the position indicated at M' the air from the inlet air-tube L is led through said duct O, as indicated at O', to the pipe H, and from thence to the lower side of said piston E, thus reversing the movement of said piston and water-controlling valves, and thereby causing the elevator to descend. As the air is thus admitted upon one side of the piston E, it exhausts from the oppo-

site side through the same pipe through which it entered, when it passes into said faucet through one of the air-ducts P P and escapes therefrom through the central duct, S. It is 5 obvious that the same movement of the handle of the air-cock which opens communication between the air-pipe L and one of said outlet-pipes H or G also opens communication from the opposite outlet-air-pipe with the central air-duct, S, through one of said air-ducts P; also, that when the handle M is thrown into the vertical position shown in Fig. 3, the inlet air-pipe L is thereby closed, and both of said outlet-pipes G and H are brought into communication with said outlet-duct S through the twin air-ducts R R, thereby relieving the cylinder F, both above and below the piston E, of compressed air when said piston is thrown to the center of the cylinder F by the action 20 of said springs a' a', as heretofore mentioned. The springs a' a' are not necessarily located in said cylinder F, as they may be connected with the valve or piston-rod outside thereof; or, if desired, the gravity of weights may be 25 substituted for the action of the springs for thus controlling the piston. For convenience in controlling the valve-operating mechanism, as described, by the operator in the elevator, said air-cock is located in the elevator and 30 connected with said valve-operating mechanism by flexible tubes G', H', and L'. When, however, it is desired to control the elevator from the several floors of a building, (as is usually the case with freight-elevators,) the 35 said air-pipes G, H, and L are in like manner connected with said air-cocks K at such places. The air-reservoir J may be charged with compressed air by any ordinary form of air-compressor; but, to insure a constant supply of 40 air at the required pressure, I preferably use an automatic hydraulic air-compressor, as

shown at A', which will continue to work until the desired air-pressure is obtained, and when such pressure is obtained it will stop of itself without the attention of an operator, and 45 resume its work again automatically as soon as the air-pressure is diminished.

Having thus described my invention, I do not confine or limit myself to the use of the same with the valve-controlling mechanism 50 shown, as it may be used equally well with any other form.

What I claim as new, and desire to secure by Letters Patent, is—

1. In a pneumatic-valve-operating device 55 for hydraulic elevators, the combination of the air-cock K, provided with inlet-pipe L, communicating between said cock and an air-chamber, air-pipes G and H, communicating between said cock, and the valve-controlling mechanism duct O, adapted to communicate between said pipe L, and either of said pipes G or H, ducts P P, R R, and exhaust-duct S, said ducts P P and R R being adapted by rotating the stopper of said cock to open communication between pipes G and H, through said exhaust-duct S, with the exterior air-pipe, L, air-receiver J, pipes G and H, and the valve-controlling mechanism, substantially as for the purpose specified. 70

2. The combination of the air-controlling cock K, provided with air-ducts O, P P, R R, and S, air-receiver J, connecting air-ducts G, H, and L, cylinder F, piston E, piston or connecting rod D, and spiral springs a' a', substantially as and for the purpose set forth. 75

In testimony whereof I affix my signature in presence of two witnesses.

WILLIAM DE BROCK.
